UNITED STATES PATENT OFFICE

165,129

LADY'S STOCKING

William G. Bley, Philadelphia, Pa., assignor of one-half to said William G. Bley and Richard C. Spurgeon, co-partners trading under the name of Bley & Spurgeon, Philadelphia, Pa., and one-half to Sanson Hosiery Mills, Inc., Philadelphia, Pa., a corporation of Delaware

Application June 23, 1950, Serial No. 10,723

Term of patent 14 years

(Cl. D47—7)

To all whom it may concern:

Be it known that I, William G. Bley, a citizen of the United States of America, residing at Philadelphia, in the county of Philadelphia and State of Pennsylvania, have invented a new, original, and ornamental Design for a Lady's Stocking, of which the following is a specification, reference being had to the accompanying drawing, forming a part hereof.

Fig. 1 of the drawing is a front elevation of a lady's stocking, showing my new design.

Fig. 2 of the drawing is an enlarged fragmentary view of the toe portion of the stocking shown in Fig. 1.

Fig. 3 of the drawing is a fragmentary view in side elevation of the foot portion of the stocking shown in Fig. 1.

I claim:

The ornamental design for a lady's stocking, as shown.

WILLIAM G. BLEY.
